Primary Examiner — Lakiya Rogers*Assistant Examiner* — Harold E Blackwell, II(74) *Attorney, Agent, or Firm* — David Weiss(57) **CLAIM**

The ornamental design for a door pull, as shown and described.

DESCRIPTION

FIG. 1 is a perspective view of a first embodiment of a door pull showing my new design;

FIG. 2 is a front elevation view thereof;

FIG. 3 is a rear elevation view thereof;

FIG. 4 is a left side elevation view thereof, the right side elevation view being a mirror image;

FIG. 5 is a top plan view thereof, the bottom plan view being a mirror image;

FIG. 6 is a perspective of a second embodiment of a door pull showing my new design;

FIG. 7 is a front elevation view thereof;

FIG. 8 is a rear elevation view thereof;

FIG. 9 is a left side elevation view thereof, the right side elevation view being a mirror image;

FIG. 10 is a top plan view thereof; and,

FIG. 11 is a bottom plan view thereof.

The broken lines in the drawings illustrate portions of the door pull which form no part of the claimed design.

1 Claim, 4 Drawing Sheets(56)
